(57) **CLAIM**

The ornamental design for a camera, as shown and described.

DESCRIPTION

FIG. 1 is a perspective view showing a camera as our novel design, which is seen from the front side obliquely from upper right side;

FIG. 2 is a perspective view thereof, which is seen from the rear side obliquely from upper left side;

FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is a left side view thereof;

FIG. 9 is a perspective view showing the camera having the lens barrier thereof opened and the photographing lens thereof extended, which is seen from the front side obliquely from upper right side;

FIG. 10 is a front view thereof showing the camera having the lens barrier thereof opened, the photographing lens thereof extended and the strobe thereof exposed; and,

FIG. 11 is a right side view thereof showing the camera having the lens barrier thereof opened and the photographing lens thereof extended.
